UNITED STATES PATENT OFFICE.

WICK HATHAWAY, OF MADISON, OHIO.

DESIGN FOR A FORK.

SPECIFICATION forming part of Design No. 34,607, dated June 4, 1901.

Application filed March 26, 1901. Serial No. 52,979. Term of patent 14 years.

To all whom it may concern:

Be it known that I, WICK HATHAWAY, a citizen of the United States, residing at Madison, in the county of Lake and State of Ohio, have invented a new and original Design for a Fork, of which the following is a specification, reference being had to the accompanying drawings, forming a part thereof.

Figure 1 is a plan view of a fork, showing my new design. Fig. 2 is a side view of the design.

As shown in the drawings, the leading or material features of my design consist of a handle portion 1, embodying a round portion 3, having produced in its upper and under surfaces a series of transversely-arranged kerfs or notches 4, extending partially around the handle and tapering from their middle in both directions. On the end of the handle portion is produced an annular flange 2, inclined inwardly to the junction with the handle. From the inner end of the round handle portion is

produced the shank 5, which is rectangular and flattened, as shown. The handle portion and shank are extended on the same axis, and from the termination of the shank are the tines 7 of the fork, produced with parallel outer lines and having their inner lines extending somewhat flaring and tapering, the base 6 of the tines being broadened and flattened and curved, the curve extending throughout the length of the tines, as shown.

Having described my invention, what I claim is—

The design for a fork, as herein shown and described.

In testimony whereof I affix my signature in presence of two witnesses.

WICK HATHAWAY.
